UNITED STATES PATENT OFFICE.

EDWIN C. LANGE AND SAMUEL J. NICHOLSON, OF CEDAR POINT, KANSAS, ASSIGNEES
OF ONE-THIRD TO CHARLES F. CAMPBELL, OF EMPORIA, KANSAS.

COIN-OPERATED LOCK.

Application filed September 22, 1927. Serial No. 221,331.

Our invention relates to improvements in coin operated locks.

The object of our invention is to provide a coin operated lock as controlling means 5 for reserved seats.

A further object of our invention is to provide a coin operated lock that may be adjusted for coins of different size and value.

10 These and other objects will be hereinafter more fully explained, reference being had to the accompanying drawings forming a part of this specification in which:

Fig. 1 is an elevation partly in section 15 for convenience of illustration.

Fig. 2 is a transverse view partly in section.

Fig. 3 is a detailed side view of the knob 20 and shaft on which the coin receiving member is mounted, a portion of the shaft removed to show the key way.

Fig. 4 is a sectional view of the coin guiding means.

Fig. 5 is a plan view of the coin slot.

25 Fig. 6 is a sectional view through Fig. 5 taken on line 6—6.

Fig. 7 is a perspective view of a seat ledge, showing the reserved seats positioned thereon.

30 Fig. 8 is a front view of one of the seats, the lid being partly open, showing the lock in action with parts removed for convenience of illustration.

Fig. 9 is a cross section through the seat 35 and lid fragmentarily, showing the spring which separates the lid from the lock.

Our coin operated lock, herein disclosed, 40 consists of a housing 1 having a lid 2 positioned on the inside thereof. Rotatably mounted in the housing is a shaft 3, having a knob 4, and may be integral therewith.

As means to secure the shaft from longitudinal movement, we have placed a collar 5 thereon, the said collar being secured by 45 a set screw 6; the knob 4 has a hub 7 to engage on the outside of the housing as spacing means for the knob from said housing, the housing positioned between the end of the hub and the collar, the opposite end 50 of the shaft rotatably engages in an aperture in the lid 2. Removably attached to the shaft and rotatable therewith is a coin receiving member 8, said member having a plurality of notches 9 radially positioned and 55 functioning as coin pockets.

Outwardly extending from the coin receiving member are pins 10 that are positioned between the notches functioning as a ratchet and means to properly position the notches in vertical alignment with the coin slot hereinafter described.

Rockably mounted in the housing is a pawl 11 that is tensioned by a leaf spring 12, the said pawl is provided with a seat 13 adapted to receive the pins 10 consecutively in their rotation; outwardly extending from the seat is a member 14 adapted to engage with an adjacent pin simultaneously with the pin in the seat.

It is now readily seen how the notches of 70 the coin receiving member are rotated to registry with the coin slot and simultaneously prevent backward rotation.

Downwardly extending from the slot is a 75 spout 15 as guiding means for the coin as it contacts with a pivotally mounted bar 16, said bar being vertically positioned and tensioned by a spring 17; on the upper end of the bar is a hook 18, adapted to engage with a hook 19, the last said hook being firmly 80 attached to a lid 20, functioning as an enclosure for a seat, as shown in Fig. 7; the first said bar has reverse curves so that the coin will contact on curve A, throwing the bar outward as shown by dotted lines B, as 85 disengaging means for the hooks.

Between the lid and seat inclosure 22 are 90 springs 23 as means to raise the lid slightly, preventing re-engagement of the lock until the lid is opened as shown in Fig. 7.

To prevent the exposure of said springs, we have positioned dowels 24 in the lid, the said dowels adapted to enter the spring aperture, by which means when the lid is opened the top of the springs will not pass from 95 their respective apertures.

When the lock is disengaged, a pin 16' functions as a stop for said bar against the tension of its respective spring.

When the mechanism is to be operated by 100 coins of different diameter, a coin receiving member is provided having notches conforming to the size of the coin; by such arrangement the peripheral edge of the coin will travel in the same arc at all times in 105 the rotation of the coin receiving member, the object of which will be to maintain the contact and action required to operate the lock bar 16 will be the same.

As means to remove and replace the coin 110

receiving member, we have provided a key way 25 in the shaft 3 and a key 26 rigidly attached in the aperture of the coin receiving member which is adapted to slidably engage in said key way.

Between said coin receiving member and the lid 2 is a coil spring 27 as tensioning means to snugly position said member against the collar 5, and in registry with the 10 spout.

It will be understood that when the coin receiving members are to be changed, the set screw in collar 5 will be removed, at which time the shaft is free to move longitudinally until disengaged from the aperture of said member, which may then be removed and replaced by another, the shaft being retracted to its normal position and the collar rigidly attached renders the mechanism in condition for further operation.

In the lid of the reserved seat adjacent the lock is positioned a slot in radial alignment with the coin receiving member, so that the coins entered therein will drop in the notch 25 of the coin receiving member, which at all times is in registry with the slot, and by rotating the said member clock-wise through the medium of the knob 4 the coin deposited therein is carried to engagement with the locking bar, forcing it outward and locking the lid, as heretofore described. After the lock is disengaged, the coin is free to drop downward into a coin receiving chamber provided for this purpose beneath the seat.

When different sized coins are to be used, a member 28 is provided with a slot to conform to the size of the coin and is interchangeable, seating within a plate 29 and rigidly attached by means of screws 30.

While I have shown the coin operated lock in connection with reserved seats, I do not confine it to this purpose alone, and such modifications may be employed as lie within the scope of the appended claims.

Having thus described my invention, what I claim as new and desire to secure by Letters Patent is:

1. In a coin operated lock, a housing and a notched coin receiving member rotatably mounted therein, an interchangeable slot and a spout as conveying means for the coins into the notches of the coin receiving member consecutively, pins outwardly extending from the sides of said member and positioned relative to the notches, a spring tensioned pawl having a seat and an extension to engage with two adjacent pins as positioning

means for the notches in registry with the slot and spout, a spring tensioned bar pivotally attached at one end, a hook on the other end to engage with a similar hook member attached to a lid as locking means for the lid, a curvature in the bar as a contact point for the peripheral edge of a coin rotated to engagement therewith by said coin receiving member and means to rotate said member.

2. In a coin operated lock, the combination of a housing, of a bar having a hook on one end, the other end pivotally connected to the housing, a spring tensioning means for the bar and a stop for the free end, of a spout having an interchangeable slot on the outer end thereof attached to the housing, of a member having a plurality of slots or pockets spaced peripherally thereon, a spring tensioned means and pins laterally extending from the side of said member to engage with said means to accurately position and detain the notches in vertical alignment with the slot consecutively to receive a coin as dropped through a slot, the coin functioning as outward rocking means for the spring tensioned bar, and conveying means for the coin when released from the notch.

3. In a coin operated lock, a coin manipulating means of the kind described, comprising a housing, a rockably mounted bar having a hook as attaching means to a hook of a lid or the like, a shaft having a knob as rotating means therefor, a collar on the shaft and means to rigidly attach thereto, as securing means for the shaft in its bearings in the housing, a notched coin receiving member, loosely keyed to the shaft and rotatable therewith, a spring coiled about the shaft as tensioning means for said member against the collar, a spout having a segmental curvature with sides between which the coin receiving member engages, the segmental portion of the spout to function as guiding means for the coin as carried to engagement with the said bar, a spring tensioned pawl to prevent anticlockwise movement of the coin receiving member, and as a stop in registry with the notches with the vertical portion of the spout consecutively as said member is rotated, all as and for the purpose described.

In testimony whereof we affix our signatures.

EDWIN C. LANGE.
SAMUEL J. NICHOLSON.
